CLAIM

The ornamental design for a collapsible rocking chair, as shown and described.

DESCRIPTION

FIG. 1 is a front elevational view of the collapsible rocking chair showing my new design in unassembled condition;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an enlarged isometric view thereof in assembled condition.

The fragmentary showing of wood graining in FIGS. 1, 2, and 7 is understood to be repeated throughout the surface shown.
